UNITED STATES PATENT OFFICE.

CHARLES C. PARK, OF KAMLOOPS, CANADA.

TIRE-TIGHTENING DEVICE.

No. 826,111.

Specification of Letters Patent.

Patented July 17, 1906.

Application filed April 12, 1905. Serial No. 255,189.

To all whom it may concern:

Be it known that I, CHARLES C. PARK, a citizen of the Dominion of Canada, residing at the city of Kamloops, in the Province of 5 British Columbia, Canada, have invented a new and useful Improvement in Tire-Tightening Devices, of which the following is a specification.

My invention relates to an improved 10 means for tightening the tire of a vehicle by pressing the rim of a wheel off the shoulder of the spokes, enabling a collar or packing to be introduced between each shoulder and the rim, whereby the rim is expanded to fit a 15 slackened tire. To attain this end, a clamp is provided which may be securely tightened on a spoke of the wheel and each clamp member is provided with a rotatable eccentric or cam, which cams may be simultaneously operated by levers, so that the movement of the eccentric will be transmitted to the rim of the wheel on each side of the spoke. While this 20 strain is on, a collar or packing may be inserted round the shoulder of the spoke. By 25 this system of tire-tightening as the spokes are individually dealt with each one is sure to be well socketed in the boss, the reaction of the outward effort on the rim tending to force the spoke downward into the boss of 30 the wheel. The device by which this operation is performed is fully described in the following specification and illustrated in the drawings which accompany it.

Figure 1 is a front elevation from the outer 35 side of a wheel, showing the application of the device; Fig. 2, a sectional plan on the line A A in Fig. 1; Fig. 3, a side elevation, to an enlarged scale, of the spoke-clamp and the rim-engaging member, the lever-handle of 40 one side being removed; and Fig. 4, a detail of the eccentric-pin in each of the clamps by which the rim-engaging members are operated.

On referring to Fig. 2 of the drawings it 45 will be seen that the clamp members 2 and 3 are shaped at their center to engage the flattened sides of a spoke 7, and their contact-surfaces may be furnished with leather or other similar material, as at 14, so that they 50 will not damage the surface of the spoke and will also enable a tighter frictional grip to be obtained without excessive tightening of the clamp members. The clamp members 2 and 3 are secured together by eyebolts 4 and 5, 55 which are each secured by pins in the member 2, the eye end being provided with two or

more pin-holes to enable adjustment to be made to suit varying sizes of spoke. The flattened portion of 5 is extended toward the threaded end and passes through a corresponding aperture in the end of the clamp member 3 to which it is attached, so that when the clamp members are disconnected at the other end they will not twist out of alignment with one another, and the end of 5 is 60 fastened in 3 with an ordinary nut. The end of the eyebolt 4 passes through a slot in its end of 3, so that the bolt may be pivotally swung aside when its nut is slackened back for the release of the clamps, and the nut is 70 provided with a lever-handle 6, by which the clamp may be readily tightened and released.

Toward the center of each clamp a hole is bored to receive a pin 8, (see Fig. 4,) having a slight head 9 on the inner side, and toward 75 the center of the bearing of these pins in the clamp a cam or eccentric 10 is turned, against which the lower end of a rim-engaging member 11 is seated, which member is rectangular in cross-section and passes through a similarly-shaped hole in the upper side of each clamp, being retained therein by a small setscrew 12, the point of which enters a groove in 11, so as to allow of free vertical movement 80 within the required limits. The upper end of 85 each of these members 11 is enlarged, as at 13, and shaped to conform to the inner side of the rim 20 and may be furnished with leather, rubber, or similar material to avoid damage to the surface of the rim.

The outer end of each eccentric-pin 8 is squared, as at 15, (see Figs. 3 and 4,) to receive a lever-handle 16, which may be secured thereon by a washer 17 and a small screw. The levers are bent inward, as shown 90 in Figs. 1 and 2, so that they may be operated simultaneously, and are so placed on the pin 8 in relation to the eccentric 10 that when they are turned to the upward position, as illustrated in Fig. 3, the eccentricity 100 of the pin is at the lowest extreme of its movement and that the movement of the lever downward to the position shown in Fig. 1 will force upward the rim-engaging members 11.

In the application of the device to expand the rim 20 of a wheel within a slack tire the eyebolts 4 and 5 are adjusted to the required length, and 4 being swung back on its pin the clamp is opened on the pin of 5 and passed on to the spoke 7, the levers 16 being to the outside of the wheel and in the upward position.

The eyebolt 4 being swung into place and the clamp lifted on the spoke until the ends 13 are set against the rim of the wheel, the clamp is tightened on the spoke by the lever-
5 nut 6. The levers 16 are then simultaneously pulled down, causing the eccentrics 10 of the pins 8 to force the members 11 up, and the tire is pressed off the shoulder of the spoke to which the device is secured. The
10 necessary thickness of collar or packing may then be inserted round the shoulder of the spoke, and the levers 16 being lifted and the
15 nut of the eyebolt 4 slackened the bolt 4 may be swung back and the clamp may be opened for removal to another spoke.

Having now particularly described my invention and the manner of its operation, I hereby declare that what I claim as new, and desire to be protected in by Letters Patent of
20 the United States, is—

1. As a tire-tightening device, the clamp members 2 and 3 adjustably connected by the members 4 and 5, the rotatable pins 8 having eccentric portions 10 and squared
25 ends 15 on which the levers 16 are secured, and the rim-engaging members 11 of rectangular cross-section fitting in similarly-shaped apertures in the upper side of the clamp members in which their movement is limited
30 by set-screws and having enlargements at their upper ends adapted to fit the rim of the wheel.

2. As a tire-tightening device, a clamp

composed of two members adapted to fit on and be secured to a spoke of a wheel, the ends 35 of the clamp members being adjustably connected together by members both of which are pivotally connected to one or the other of the clamping members, one of the clamping members being susceptible of being swung 40 aside on its pivot-pin clear of the other clamping member, a rotatable pin in each of the clamping members having an eccentric portion within its bearing in the clamp, and a squared portion on the outside of the bearing 45 of the clamp, a handle member on the squared portion of said pins, and means for securing the handle member to said pin, rim-engaging members vertically slidable on the upper side of the clamp members so that their lower 50 ends may rest on the eccentric portion of the pins, means for tightening the clamp members on the spoke, said handle members being arranged to rotate the pins so that the movement of the eccentric portions thereof 55 may be imparted to the rim-engaging members and to the rim, substantially as described.

In testimony whereof I have signed my name to this specification in the presence of 60 two subscribing witnesses.

CHARLES C. PARK.
